UNITED STATES PATENT OFFICE.

HENRY F. BECHMAN, OF BATTLE CREEK, MICHIGAN, ASSIGNOR TO DUPLEX PRINTING PRESS COMPANY, OF BATTLE CREEK, MICHIGAN.

MEANS FOR FASTENING PLATES TO CYLINDERS.

No. 823,099.

Specification of Letters Patent.

Patented June 12, 1906.

Application filed August 4, 1905, Serial No. 272,684.

To all whom it may concern:

Be it known that I, HENRY F. BECHMAN, of Battle Creek, in the county of Calhoun and State of Michigan, have invented certain new and useful Improvements in Means for Fastening Plates to Cylinders; and I hereby declare that the following is a full, clear, and exact description thereof, reference being had to the accompanying drawings, which form part of this specification.

This invention relates to rotary-cylinder printing-presses, and has particular reference to the plate-cylinders thereof; and it consists in novel means for attaching or fastening the stereotype or other curved-plate printing-surfaces to the peripheries of the plate-cylinders.

The invention is particularly adapted to cylinders carrying a multiplicity of plates, such as four-page-wide cylinders; and its objects are to enable each plate to be securely fastened thereto in an expeditious manner, the inner plates being secured first and the devices for operating the clamps for the outer plates being utilized as the means for operating the clamps for the inner plates, the clutch between the two devices being discon-nectible, so that the fastening or unfastening of the outer plates does not affect the fastening of the inner plates.

The invention will be clearly understood from the accompanying drawings and the following description, and the features for which protection is desired are stated in the claims appended hereto.

The said drawings illustrate the invention as applied to a "four-page-wide" plate-cylinder of a newspaper printing-press, Figure 1 being a side elevation of part of a four-page-wide plate-cylinder of a rotary printing-press, provided with my novel plate-clamping devices. Fig. 2 is an enlarged detail plan view of the plate-clamping devices. Fig. 3 is a longitudinal section on line 3 3, Fig. 2; and Fig. 4 is a transverse section on line 4 4, Fig. 2.

The plate-cylinder A is provided with a central annular rib a, undercut on its sides to engage and retain the inner beveled edges of stereotype-plates S or other printing-surfaces of ordinary formation. The cylinder is also provided with a series of parallel longitudinal slots B in its periphery, extending from its outer end toward the central rib, these slots

being preferably T-shaped or dovetailed in 55 cross-section, so as to retain and guide the plate-clamps C and D, the former being the inner clamps and the latter the outer clamps.

The clamp-bodies are fitted to and slide in the grooves B, and their outer portions or 60 heads c d project slightly beyond the periphery of the cylinder. The heads c of clamps C are undercut on both sides, so as to engage and retain the edges of adjacent stereotype-plates S on each side thereof, as shown in 65 Fig. 1, while the heads d of clamp D need only be undercut on their inner edges, as they engage only the outer edges of the outermost plates S.

Each clamp C is transfixied by a threaded 70 rod E, which is arranged within the slot B and is stepped at its inner end into a bearing e at the inner end of slot B, and near its outer end rod E is supported in a bridge-piece E', secured within and across the slot B, as 75 shown, rod E having a collar e' on it at the inner side of bridge-piece E', which permits the rod E to be rotated, but prevents longitudinal movement thereof. Obviously the rotation of rod E will cause clamp C to travel 80 along the rod in slot B. The clamp D is similarly transfixied by a threaded rod F, the inner end of which is preferably stepped into the outer end of rod E, as shown at F', adja- 85 cent to bridge-piece E', and the outer end of rod F extends through bridge-piece f in the outer end of the slot B, a collar f' on the rod F preventing it moving longitudinally, al- though it can be readily rotated by a wrench or other manipulating device applied to its 90 squared outer end F², which projects slightly beyond the face of the outer end of the cylinder. The adjacent ends of the rods or rod-sections E and F are both squared, as shown at E² F², the squared part F² of rod F being 95 longest, and on this part is placed a loose sleeve G, whose bore is shaped to fit the squared part of the rods. When sleeve G is moved outward, so as to be entirely on rod F, the latter can be rotated without affecting 100 rod E; but when sleeve G is moved inward, so as to also engage part E² of rod E, as indicated in dotted lines G², it forms a clutch connection between the two rods E F, so that one cannot be turned without the other, and 105 therefore by rotating rod F rod E will be rotated also. Thus clamp C can be shifted back or forth by rotating rods E F when

coupled together, and when sleeve G is moved back out of engagement with rod E the clamp D can be adjusted by rotating rod F without affecting clamp C.

5 Operation: When plates S are to be secured to the cylinder, the sleeves G are shifted so as to engage rod-sections E and lock them to rod-sections C. Then the rods are turned to back clamps C outward until the 10 plates S can be placed on the cylinder between rib a and clamps C. Then rods E F are turned so as to move clamps C up against the outer edge of the inner plates S and secure the latter in place. The operator then 15 disengages sleeves G from rods E by slipping the sleeves outward by hand and then backs clamps D outward by rotating rods F (sections E remaining unaffected) until the outer plates S can be placed on the cylinder between 20 clamps C and D. Then the clamps D are moved inward until they bind the plates between them and clamps C, as shown in Fig. 1, and the operation is completed. When the outer plates S are in position, the sleeves 25 G are covered, so that it is necessary to remove said plates before sleeves G can be shifted.

From the foregoing it will be noted that the clamps are virtually operated by a sectional rod, one part of which may be locked or unlocked from the other by means of clutches or clamps of simple construction; that this device avoids the necessity for independent slots in the cylinder for the inner 30 and outer clamps and dispenses with separate operating mechanism for the inner clamps. Thus the strength of the cylinder is enhanced, less operative parts are required, and the clamp-operating devices are 35 more compact, and all clamps can be positively adjusted and remain locked when adjusted by the screw-rods. Also the clamps can be operated from the end of the cylinder, which is the most convenient and accessible 40 place for using the manipulating tool or wrench. Obviously, also, the invention is not 45

restricted to the specific sleeve-clutch nor to the specific number of clamps and rod-sections shown in the drawings.

Having thus described my invention, what 50 I claim as new, and desire to secure by Letters Patent, is—

1. In combination a plate-cylinder having slots, rods in said slots, a disconnectible connection between the ends of adjacent rods, 55 and plate-clamps in said slots respectively actuated by the rods.

2. In combination with a plate-cylinder having longitudinal slots, of alined threaded rod-sections in said slots, an operative connection between the ends of adjacent sections, and plate-clamps in said slots respectively transfixed by the rod-sections, whereby the several clamps may be adjusted. 60

3. In combination a plate-cylinder having 65 a longitudinal slot, a set of plate-clamps in said slot movable longitudinally thereof, a threaded rod-section transfixing each clamp, said sections being in alinement, and rotatable but longitudinally immovable in the 70 slot, and a longitudinally-movable member on the end of one section adapted to be slipped endwise to engage the end of the adjacent section and lock the sections together.

4. The combination of a plate-cylinder 75 having longitudinal slots, and a set of plate-clamps in said slot movable longitudinally thereof; with a rotatable but longitudinally-immovable threaded rod transfixing each clamp, said rods being in alinement and the 80 adjacent ends of said rods being squared, and a longitudinally - movable sleeve on the squared end of one rod adapted to be slipped endwise thereon to engage or disengage the 85 squared end of the adjacent rod.

In testimony that I claim the foregoing as my own I affix my signature in presence of two witnesses.

HENRY F. BECHMAN.

In presence of—

ARTHUR G. STERLING,
FRANK W. DUNNING.
